US00D625841S

(12) **United States Design Patent**
Mugge et al.

(10) **Patent No.:** US D625,841 S
(45) **Date of Patent:** ** Oct. 19, 2010

(54) **MOLDED SURFACE OF A CONCRETE PRODUCT**

(75) Inventors: **Jimmie L. Mugge**, Inver Grove Heights, MN (US); **Jay J. Johnson**, Star Prairie, WI (US)

(73) Assignee: **Anchor Wall Systems, Inc.**, Minnetonka, MN (US)

(**) Term: **14 Years**

(21) Appl. No.: **29/349,102**

(22) Filed: **Mar. 8, 2010**

Related U.S. Application Data

(62) Division of application No. 29/315,591, filed on Jul. 6, 2009, now Pat. No. Des. 613,880, which is a division of application No. 29/313,100, filed on Dec. 5, 2008, now Pat. No. Des. 598,137, which is a division of application No. 29/286,614, filed on May 14, 2007, now Pat. No. Des. 585,567.

CLAIM

The ornamental design for a molded surface of a concrete product, as shown and described.

DESCRIPTION

FIG. 1 is a perspective view of a molded surface of a concrete product, according to our new design, the portions shown in broken lines forming no part of the design sought to be patented;

FIG. 2 is a front view of the surface depicted in FIG. 1, the portions shown in broken lines forming no part of the design sought to be patented;

FIG. 3 is a right side view of the surface depicted in FIG. 1, the portions shown in broken lines forming no part of the design sought to be patented;

FIG. 4 is a left side view of the surface depicted in FIG. 1, the portions shown in broken lines forming no part of the design sought to be patented;

FIG. 5 is a top view of the surface depicted in FIG. 1, the portions shown in broken lines forming no part of the design sought to be patented; and,

FIG. 6 is a bottom view of the surface depicted in FIG. 1, the portions shown in broken lines forming no part of the design sought to be patented;
